UNITED STATES PATENT OFFICE.

ADOLF P. WITTE, OF CHICAGO, ILLINOIS, ASSIGNOR OF ONE-HALF TO MAURICE S. DICK,
OF CHICAGO, ILLINOIS.

ELECTRIC-SWITCH CONTACT-HOLDER.

1,212,867.

Specification of Letters Patent. Patented Jan. 16, 1917.

Application filed February 11, 1896. Serial No. 77,731.

To all whom it may concern:

Be it known that I, ADOLF P. WITTE, a citizen of the United States, and a resident of Chicago, county of Cook, and State of Illinois, have invented certain new and useful Improvements in Electric-Switch Contact-Holders, of which the following is declared to be a full, clear, and exact description.

This invention relates to electric switch contact holders, and its primary object is to provide simple and improved means whereby the carbon contact block may easily and quickly be removed from its holder and replaced by a new one when worn out, or in case of breakage.

The invention has been designed particularly for use in connection with reverse switch mechanism of electric elevators, but it is to be understood that its use is not limited thereto as there are many situations where a carbon contact block holder of the present type is capable of use.

This invention consists of the several novel features hereinafter fully set forth and claimed.

This invention is clearly illustrated in the accompanying drawing in which:

Figure 1, is a view partly in section and partly in side elevation of a portion of an electric reversing switch, showing two carbon contact block holders embodying the present invention, applied to said switch; Fig. 2, is a cross section taken on the line 2--2 of Fig. 1; Fig. 3, is an end view of the holder, looking in the direction of the arrow 3, in Fig. 1; Fig. 4, is a perspective view of the holder; Fig. 5, is a perspective view of the carbon contact block used in connection with the holder; and Fig. 6, is a perspective view of a latch plate used with the holder.

In said drawing, the reference numeral A, designates a support which may be composed of slate or other non-conducting material, and to said support are secured carbon contact block holders 11; there being as many holders as are necessary for the operation of the switch. In the drawing, two holders are shown, one on each side of the support A, and below said holders is a rocking contact member 12, which has carbon contact blocks 13, upon its ends, that are adapted to be brought into contact with the carbon blocks 14, for the purpose of closing electrical circuits; said rocking contact member 12, is shown as mounted upon a shaft 15, which

may be rocked by any suitable controlling mechanism, (not shown).

The contact block holding member comprises a fixed or stationary plate 16, having a stem 17, which projects up through a hole 60 in the support A, and is secured in place by a nut 18, threaded upon the end of the stem 17. The electric conductor cord 2, may be secured in place between the nut 18, and a washer, as is customary. Slidably carried 65 by said plate 16, is a movable contact block holding plate 19, to which is secured two pins 20, that extend through holes in the fixed plate 16, and have headed ends 21, which strike against the plate 16, and limit 70 the downward movement of the movable plate 19. Coiled compression springs 22, encircling the pins 20, are confined between the fixed plate 16, and movable plate 19, and act to yieldably hold said movable plate 75 away from the fixed plate. If desired, an electric conductor cord 23, may be connected to the plates 16, 19, for making electrical connection therebetween. The support A, is formed with holes 24, lying parallel with the 80 hole for the stem 17, said holes 24, are intended for the reception of the headed pins 20.

The plate 19, is formed with a rectangular opening, or notch 25 (see Fig. 4) which extends back from one edge of the plate, and the carbon block 14, is formed with two oppositely disposed grooves 26, and a cross groove 26¹; that are adapted for the reception of the marginal edges 25¹, 25², of the notch 25. If desired, a rib 27, may be formed upon one face of the plate 19, to engage with one face of the carbon block. The carbon block is fastened in place upon the plate 19, by bringing the grooves 26, in register with the edges 25¹ of the opening, or notch, 25, and then sliding the block back until it seats against the edge 25², of the opening or notch 25, after which it is prevented from accidental removal by a latch plate 28, which is fastened in place across the gap in the plate. Said latch plate has a notch 29, in one end adapted for engagement with a headed pin 30, on the edge of the plate 16, and also has a transversely extending notch 31, near the other end adapted for engagement with a headed pin or lug 32, on the edge of the plate. When placing the latch on the plate 19, the notch 29, is first engaged with the lug 30, after which the latch is swung down to 100 105 110

bring the notch 31, in engagement with the lug 32.

In case a carbon block becomes worn or broken, the latch 28, is detached from the 5 lugs 30, 32, the carbon block slipped off the plate 19, and a new carbon block inserted, after which the latch may be re-attached to the lugs or pins 30, 32.

More or less variation of the exact details 10 of construction is possible without departing from the spirit of this invention, and I desire therefore, not to limit myself to the exact construction shown and described, but intend in the following claims to point out 15 all of the invention disclosed herein.

I claim as new and desire to secure by Letters Patent:

1. A carbon contact block holder, comprising a supporting plate, having a screw 20 threaded stem, and arranged to be fixedly secured to a support, a carbon contact block holding plate, having a rectangular notch extending in from one edge adapted to receive a grooved carbon block with the edges 25 adjacent the notch of the notched plate entering the grooves of the carbon block, two

headed pins secured to said block holding plate, and slidably guided in apertures in said supporting plate; the heads of said pins being arranged to limit movement of said 30 block holding plate in one direction, springs interposed between said plates, and a latch adapted to be secured to said block holding plate in front of said notch, to thereby removably hold the block in place. 35

2. A carbon contact block holder, comprising a fixed supporting plate, having a pair of apertures therein, a carbon block holding plate, having an upwardly opening notch formed therein and having a pair of 40 headed pins sliding in said apertures; the heads of said pins being arranged to strike against the supporting plate to thereby limit movement of the block holding plate in one direction, springs interposed between said 45 plates, a grooved carbon contact block removably held in the notch of said block holding plate, and a latch removably secured to said holder above the block whereby the carbon block may be removed without removal of the holder from its support. 50

ADOLF P. WITTE.
